UNITED STATES PATENT OFFICE.

EDWARD T. CONDON, JR., OF NEW YORK, N. Y.

AUTOMATIC STOP MECHANISM FOR TALKING-MACHINES.

1,351,839.

Specification of Letters Patent. Patented Sept. 7, 1920.

Application filed October 17, 1916. Serial No. 126,070.

To all whom it may concern:

Be it known that I, EDWARD T. CONDON, Jr., a citizen of the United States, and a resident of New York, in the county of New York and State of New York, have invented certain new and useful Improvements in Automatic Stop Mechanism for Talking-Machines, of which the following is a specification.

The invention relates to talking machines, and more particularly to mechanism for automatically effecting the stopping of the turn-table for the record at the completion of a selection. It has for its object to provide a device of this character which shall be simple in construction, self-contained, and efficient in its action. A further object of the invention is to afford a brake mechanism which shall be operative, simultaneously with its setting for a particular record, to free its turn-table for the rotation thereof. The mechanism, moreover, is adaptable to talking machines in which the stylus operates either from the outside of the record toward the center, as is the general practice, or vice versa.

The nature of the invention will be best understood when described in connection with the accompanying drawings, in which—

Figure 1 is a front elevation, partly in section, of the upper portion of a talking machine equipped with the improved stop mechanism.

Fig. 2 is a plan thereof with portions broken away.

Figs. 3 and 4 are detail views, partly in section, illustrating the operation of the stop mechanism.

Figs. 5 and 6 are detail perspective views of parts of the automatic stop mechanism.

Similar characters of reference designate corresponding parts throughout the several views.

Referring to the drawings, 10 designates the top or motor board of a talking machine, comprising the usual turn-table 11 adapted to be suitably rotated, by suitable mechanism (not shown) through shaft 12, and to support the record 13. The latter is adapted to be engaged by a stylus 14 of sound box 15 carried by tone arm 16, the horn 17 of the talking machine being herein described and shown, by way of example, as of the concealed type. A tone arm base 18 is mounted, in this embodiment, over the inner end of

said horn 17 and receives the inner end of the tone arm 16, supporting same so as to be rotatable about the vertical axis of the base 18 as well as about a horizontal axis at right angles thereto. For this purpose, the inner end of tone arm 16 carries a rod 19 extending diametrically therethrough, its protruding ends forming trunnions adapted to engage in a circular groove 20 of a cap or base 21 set in the upper end of the tone arm base. The lower end of cap 21 forms one face of a raceway 22 in the wall of tone arm base 18, and in which raceway is mounted a set of balls 23 to provide a free bearing for a collar 24 retained thereby within said tone arm base. Said collar is provided with a peripheral groove 24' for said balls and retains internally a frictionally mounted spring ring or open annular member 25 fitting the same snugly and movable normally therewith. Said ring is provided with a fork 26 extending radially inward and engaged by a rod 27 extending downwardly from the inner end of the tone arm 16 into the tone arm base and through said fork, whereby the ring 25 and collar 24 are caused to move as a unit with said tone arm 16. Collar 24, moreover, is provided with an opening 28 through its wall and is adapted to register with a similar opening 29 through the wall of the tone arm base 18 and to receive the inner end of a rod 30 passing through the opening 29. Under these conditions, collar 24 may be locked with respect to the tone arm base and ring 25 moved relatively thereto with the tone arm 16, the movement of both ring and tone arm being limited by contact between the projecting end of rod 30 with the ends of the said ring.

Rod 30 is spring-urged toward the opening 28 by means of a spring 31 coiled about its outer end and acting against a shoulder 32 thereon and a lug 33 extending from the motor board 10. When locked in the opening 28, the spring 31 is so adjusted that a brake member 34 mounted on the rod will engage the inner wall of rim or down-turned flange portion 35 of the turn-table to stop its rotation. A downwardly extending pin 36 of said rod 30 is provided with a sleeve 37 of insulating material which is adapted to engage the two tongues 38 of a switch member to open, as indicated in Fig. 4, or to close, as indicated in Fig. 3, suitable con-

tacts 39, the former condition existing when the brake member 34 operates to stop the rotation of table 11.

It will be understood that the electrical portion of this mechanism will be required only where the turn-table is rotated by an electric motor, the circuit to which is controlled by said contacts 39 through conductors 40 leading therefrom, as is well understood.

In order to release the brake 34 and to close contacts 39, thereby starting the rotation of table 11, and to set the mechanism for effecting the stopping of the record at the completion of the selection, the tone arm 16 is brought in position such that its stylus will engage the last (inner or outer as the case may be) groove of the record—for example, tone arm axis in position *b*—*b*, Fig. 4. The rod 30 is then manually withdrawn from the collar 24 and held in opposition to the spring 31 until the openings no longer register, the tone arm being returned to the desired starting position—with axis in position *a*—*a*, Fig. 3—and the stylus 14 caused to engage the record 13. The collar 24 with ring 25 is thereby rotated with the tone arm and is in such position that the inner end of rod 30 presses against the outer surface of collar 24, and the said rod, therefore, is maintained in its retracted position, permitting free rotation of the turn-table 11. At the completion of the selection, collar 24 will have returned to position set and such that the two openings 28 and 29 will again register. Thereupon, the inner end of rod 30 will reenter the opening 28, causing brake member 24 to engage flange 35 and contacts 39 to be opened, thus stopping the rotation of said turn-table. It will be understood that owing to the frictional engagement between the ring 25 and its collar 24, tone arm 16 may be oscillated freely while the turn-table 11 is at rest, the collar 24 being locked against rotation by the inner end of said rod 30.

I claim:

1. Automatic stop mechanism for talking machines, comprising: the tone arm of the machine, and a base in which the same is mounted; a collar within said base, rotatable with the tone arm and provided with an opening; and brake actuating mechanism including means adapted to engage said opening of the collar.

2. Automatic stop mechanism for talking machines, comprising: the tone arm of the machine, and a base in which the same is mounted, said base being provided with an opening; a member within said base, movable with said tone arm and having an opening adapted to register with said opening of the base; and brake actuating mechanism including means adapted to engage both of

said openings to effect the stopping of the rotation of the talking machine turn-table.

3. Automatic stop mechanism for talking machines, comprising: the tone arm of the machine, and a base in which the same is mounted, said base being provided with an opening; a member within said base, movable with said tone arm and having an opening adapted to register with said opening of the base; and brake actuating mechanism including means adapted to engage both of said openings to effect the stopping of the rotation of the talking machine turn-table and to be retracted from one of said openings.

4. Automatic stop mechanism for talking machines, comprising: the tone arm of the machine, and a base in which the same is mounted; means within said base, rotatable with said tone arm; a brake actuating member adapted to engage same to effect the stopping of the rotation of the talking machine turn-table; and a member movable with said tone arm relatively to said means rotated by the tone arm.

5. Automatic stop mechanism for talking machines, comprising: the tone arm of the machine, and a base in which the same is mounted; a collar within said base, rotatable with said tone arm and provided with an opening; brake actuating mechanism including a rod adapted to engage said opening of the collar; and a ring frictionally retained in said collar and movable by said tone arm.

6. Automatic stop mechanism for talking machines, comprising: the tone arm of the machine, and a base in which the same is mounted; a collar within said base, rotatable with said tone arm and provided with an opening; brake actuating mechanism including a rod adapted to engage said opening of the collar; a ring frictionally retained in said collar and movable by said tone arm; and a member extending from said tone arm adapted to engage said ring.

7. Automatic stop mechanism for talking machines, comprising: the tone arm of the machine; a collar rotatable therewith and provided with an opening; brake actuating mechanism including a rod adapted to engage said opening of the collar; a ring frictionally retained in said collar having a fork extending radially therefrom; and a rod extending downwardly from said tone arm through said collar and the fork of its said ring.

8. Automatic stop mechanism for talking machines, comprising: the tone arm of the machine, and a base in which the same is mounted, said base being provided with an opening; a collar provided with an opening adapted to register with the said opening of the base; a ball bearing for mounting the collar in the said base; brake actuating

mechanism including a rod adapted to engage said openings; a ring frictionally retained in said collar having a fork extending radially therefrom; and a rod extending 5 downwardly from said tone arm through said collar and the fork of its said ring. 15

9. Automatic stop mechanism for talking machines, comprising: the tone arm of the machine, and a base in which the same is 10 mounted; a collar within said base, rotatable

with said tone arm and provided with an opening; brake actuating mechanism including a rod spring-urged toward said opening of the collar to engage the same; and a ring frictionally retained in said collar and movable by said tone arm.

Signed at New York, in the county of New York and State of New York, this 13th day of October, A. D. 1916.

EDWARD T. CONDON, JR.
